UNITED STATES PATENT OFFICE.

WILLIAM H. BERGER, OF PHILADELPHIA, PENNSYLVANIA.

DESIGN FOR A HANDLE FOR CUPS, &c.

SPECIFICATION forming part of Design No. 17,360, dated May 31, 1887.

Application filed June 29, 1886. Serial No. 206,657. Term of patent 14 years.

To all whom it may concern:

Be it known that I, WILLIAM H. BERGER, a citizen of the United States, residing in the city of Philadelphia, county of Philadelphia, 5 and State of Pennsylvania, have invented a new and original Design in Handles for Picnic-Cups and for other Dishes, of which the following is so full, clear, and exact a description as will enable others skilled in the art to 10 which my invention appertains to make and use the same, reference being had to the accompanying drawings, in which—

Figure 1 is a cross-section of a cup provided with one of my handles. Fig. 2 is a perspective of my handle, showing the ornamentations *a a* as depressed into the body. Fig. 3 is a cross-section of the handle. Fig. 4 is a perspective showing the ornamentations *a a* as projecting from the body of the handle. Fig. 20 5 is an enlarged plan view of Fig. 4. Fig. 6 is a smaller plan view of Fig. 4.

The main features of my design consist in the ornamentation of the outer portion of the body of the handle.

25 Another important feature is the prominent projection on the top of the handle just above the upper curve in the main portion of the handle.

Another valuable feature is the upper curve 30 in the handle, which extends above the plane of the line of the top of the cup.

Another feature of my invention is the inner double flange each side of the main part of the handle.

35 Still another feature is the row of serrations on the outer portion of the main part or body of the handle.

Still another prominent feature, and one which catches the eye, is the little projection 40 on the inner face of the upper curve.

The body A is provided with two flanges, D D. Each side of the main portion of the handle, and on the outside of the body A, is a series of corrugations, *b b b*. Each side of the 45 body A is provided with a series of ornamentations, *a a a a*, which may be depressed into the handle, or they may be cast on the handle

in a row of projecting points or heads, the general effect being the same whether they be raised or depressed.

The body A is provided with a flattened or enlarged surface at B and C, respectively. From the flattened portion C the body extends outwardly and downwardly, forming a projection, *e*, on the lower portion of the handle, and it then curves outwardly and upwardly to the point *g*, where it again curves downwardly and inwardly to the enlarged portion B. Just between the enlarged portion B and the upper curve in the body A is a projection, 55 *h*, which stands out quite prominently and corresponds with the projection *e* near the lower enlarged portion C.

At the top of the handle, and on the outside of the upper curve of the body A, is a projection, E, which stands out boldly and conspicuously on the top of the handle. The happy combination of these elements all go to make up a neat little handle for a cup, and the general effect is pleasing to the eye of the user.

It is obvious that many of the slight details may be varied without destroying the general effect of my design; but

What I deem of importance, and what I consider the main features of my invention, and what I therefore claim, is—

1. In a design for handles, the body of the handle provided with the upper and lower flattened portions, B C, the outer edges of said body portion being corrugated, a serrated portion, E, interposing and projecting above the corrugations, as shown and described.

2. In a design for handles, the body provided with flanges and a series of corrugations on its outer portion, and also having a series 85 of ornamentations, *a a a*, on either side of the body, as shown and described.

In testimony whereof I affix my signature in presence of two witnesses.

WILLIAM H. BERGER.
